Fig. 5

FIG. 1 is a front elevational view of a urinal drainage bag showing our new design;

FIG. 2 is a top plan view thereof;

FIG. 3 is a bottom plan view thereof;

FIG. 4 is a section, on an enlarged scale, taken on line 4-4 of FIG. 2;

FIG. 5 is a rear elevational view thereof;

FIG. 6 is an end elevational view thereof, looking from the left with respect to FIG. 1; and

FIG. 7 is an elevational view of the other end thereof.

We claim:

The ornamental design for a urinal drainage bag, substantially as shown.
